COLLAPSIBLE TELESCOPE STAND

Herbert H. Kirby and Charles B. Thorington,
Long Beach, Calif.

Application May 5, 1948, Serial No. 25,176

1. Claim. (Cl. 248—170)

1 The present invention relates to new and useful improvements in stands for supporting a telescope and more particularly to a collapsible stand for use by riflemen in a prone position to hold a spotting telescope in a manner whereby the telescope may be lined up with one of the eyes of the rifleman while he is aiming with the other eye.

An important object of the invention is to provide a collapsible stand of this character so constructed that no part of the rifleman's arm can touch the stand when in proper firing position and including a base composed of right angularly disposed horizontal arms for resting on the ground and pivoted to the lower end of an upstanding post having a bracket at its upper end for supporting the telescope thereon, the arms being foldable against the post for convenient transportation or storage purposes.

A further object of the invention is to provide means for vertically adjusting the bracket at the upper end of the post as well as for adjusting the angle of the telescope secured thereto.

A still further object is to provide a device of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figure 2 is a front elevational view;

Figure 3 is a side elevational view showing the base in folded position;

Figure 4 is a side elevational view of the adjustable telescope supporting bracket;

Figure 5 is an enlarged fragmentary side elevational view of the bracket with parts broken away and shown in section, and

Figure 6 is a sectional view taken substantially on the line 6—6 of Figure 5.

Referring now to the drawings in detail wherein for the purpose of illustration we have disclosed a preferred embodiment of the invention the numeral 5 designates the stand generally and which is constructed of a pair of elongated base members or arms 6 and 7 pivotally attached to the lower end of an angle iron post 8 to position the arms at right angles with respect to each other when in an open position resting on the ground. The lower end of the post 8 pro-

jects downwardly below the inner ends of the arms 6 and 7 to provide a prong 9 for penetrating into the ground.

The post is supported in an inwardly inclined position by means of stops 10 at each side of the post and with which the upper edges of the arms respectively engage. The arms 6 and 7 are pivoted to the post by means of bolts and nuts 11 whereby the arms and post may be rigidly connected to each other when in open position to rigidly hold the post in its upstanding position.

The upper end of the post is formed with a socket 12 in which a stem 13 is slidably and rotatably adjustable and held in its vertically and horizontally adjusted position by a set screw 14 carried by the socket. A collar 15 is vertically adjustable on the stem by means of a set screw 16 and which rests upon the top of the socket 12 to hold the stem in its vertically adjusted position while the set screw 14 holds the stem in its horizontally adjusted position following the vertical adjustment thereof.

The upper end of stem 13 is curved to form a goose neck 17 which is pivoted to one end of a substantially bellcrank plate 18 and which in turn is pivoted at a central portion to a horizontal V-shaped clamping plate 19.

The other end of the plate 18 is provided with a socket 20 in which a ball 21 is swivelly held and carried at the inner end of an adjusting screw 22 threaded through an apertured boss 23 at the adjacent end of the clamping plate 19. The outer end of the adjusting screw is provided with a knurled knob 24 and a coil spring 25 is positioned between the boss 23 and the plate 18 to tensionally hold the adjusting screw in its adjusted position.

A clamping band 26 extends around the clamping plate 19 and a telescope 27 to hold the telescope firmly in the angle of the clamping plate.

In the operation of the device the stand is set up with the arm 6 extending transversely in front of a rifleman 28 in a prone position and the arm 7 extending rearwardly at one side of the rifleman. The post 8 is thus supported in a rearwardly and inwardly inclined position at the pivoted ends of the arms and the stem 13 is then adjusted vertically and horizontally to a correct position for aligning the rear end of the telescope 27 with one eye of the rifleman while he aims a rifle 29 with his other eye. The angle of the telescope is adjusted by the adjusting screw 22 which tilts the clamping plate 19 for the telescope upwardly or downwardly as desired.

The stand is collapsed by removing the tele-

scope from the clamping plate 19, removing the stem 13 and bracket 18 from the upper end of post 8 and folding arms 6 and 7 downwardly from stops 10 and upwardly against the sides of the post.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of, the appended claim.

Having described the invention, what is claimed as new is:

A telescope stand comprising a base composed of a post, a pair of horizontal arms pivoted to the lower end of the post for folding against the post and positioned substantially at right angles to each other to support the post in an upstanding position, a stem carried at the upper end of the post for vertical sliding and horizontal ro-

10 tary adjustment, a V-shaped clamping plate for holding a telescope, and means connecting the clamping plate to one side of the stem for adjusting the angle of a telescope attached to the plate and including a substantially bellcrank lever to which the plate is pivoted, and an adjusting screw between the plate and the lever.
